CLAIM

The ornamental design of a stackable tray with tabbed lid, as shown and described.

DESCRIPTION

FIG. 1 is a perspective view of a stackable tray with tabbed lid according to the inventive design in the form of a glued blank;

FIG. 2 is a top plan view thereof;

FIG. 3 is a front elevational view thereof;

FIG. 4 is an elevational view of one side, the other side being a mirror image thereof;

FIG. 5 is a bottom plan view thereof; and,

FIG. 6 is a perspective view of the stackable tray with tabbed lid after the glued blank therefor has been erected.

The broken line showing on FIG. 1, 2 and 4 represent fold lines.
